UNITED STATES PATENT OFFICE.

JESSE GERALDUS PICKERING, JR., OF NASHVILLE, TENNESSEE.

LIFTING JACK.

Application filed October 2, 1924. Serial No. 741,227.

To all whom it may concern:

Be it known that I, JESSE GERALDUS PICKERING, Jr., a citizen of the United States, residing at Nashville, in the county of Davidson and State of Tennessee, have invented certain new and useful Improvements in Lifting Jacks, of which the following is a specification.

This invention relates to lifting jacks, and more particularly to a construction adapted for use as a single or double acting jack and which has the advantage of quickly elevating the object to be lifted, or on the other hand, quickly lowering the same.

One of the objects of the invention is to provide a simple and practical construction that may be readily collapsed into compact form, and yet is extensible to a maximum distance when desired or required, thereby materially increasing its range of use. In that connection it is also proposed to provide a construction that is dust proof and easy to operate.

A further object of the invention is to provide a jack having means for engaging objects to be lifted at various heights in a convenient and practical manner.

A still further object of the invention is to provide a novel arrangement of lifting and sustaining pawls which makes the jack fulfill the requirements of either a single or double acting jack.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:

Figure 1 is a view illustrating the jack in use, the rack bars thereof being manipulated into elevated positions.

Figure 2 is a detail side elevation of the jack collapsed.

Figure 3 is an enlarged vertical sectional view of the jack with the parts as in Figure 2.

Figure 4 is a horizontal sectional view taken on the line 4—4 of Figure 3.

Figure 5 is a view similar to Figure 3 showing the lifting pawls at the upward limit of their lifting movement.

Figure 6 is a view similar to Figures 3 and

5 illustrating the relative position of the lifting pawls and sustaining pawls during the descent of the jack.

Figure 7 is a detail horizontal sectional view taken on the line 7—7 of Figure 2.

Figure 8 is a detail perspective view of the adjustable lifting lug.

Similar reference characters designate corresponding parts throughout the several figures of the drawings.

The invention in its general organization includes a casing designated generally as A which serves both as a housing for the rack bars B and C, as well as an intermediate 70 member of the jack as clearly shown in Figure 1.

The rack bar B is provided with a base or foot portion D while the rack bar C is provided with a lifting horn E, the said base D and horn E being offset from their respective rack bars in opposite directions, and the rack bars each being provided with grooves G for engaging with the ribs R of the casing A and its cover A' (see Fig. 4). This arrangement permits the rack bars to be slidably guided in the opposite sides of the casing A in a stable and practical manner thereby to provide a rigid structure for distributing the load sustained by the jack. 80

One of the novel features of the invention resides in the provision of an adjustable supporting lug F which is bifurcated at F' in Figure 8 and thereby adapted to straddle the casing A and its cover A' as shown in Figures 1 and 2, whereby, in co-operation with the shoulders F² in one edge of the casing and the lugs F³ on the sides thereof, the said lug F will be held in any desired adjusted position at one edge of the casing. To prevent accidental longitudinal displacement of the lugs F, the abutments F⁵ may be provided with the ribs F⁴ which cooperate with the recesses F⁶ of the lugs as shown in Figures 1 and 2, thereby serving 90 to prevent the lateral slipping of the lugs while the jack is being manipulated to lift the load. 95

Referring to Figure 1, and assuming the rack bar B to be relatively stationary, the casing A and rack bar C may be moved relative to the said rack bar B when the handle H of the novel elevating means M (Fig. 2) employed herein is actuated. This elevating means preferably consists of an actuator 1 110 (Fig. 3) comprising a body formed with opposite bearing portions 2 and 3 respectively

journalized in the side wall of the casing A and the cover A' as shown in Figure 4, and having the oppositely extending bifurcated wings 4-4. The said wings 4-4 have 5 pivotally fitted therein, the oppositely extending lifting pawls 5-5 whose free ends 6 are adapted to engage respectively with the rack bars B and C while the intermediate portions thereof are engaged by the springs 10 7 thereby normally to force the said ends 6 of the lifting pawls into engagement with the reversely arranged shoulders of the racks. The bearing portion 2 is provided with a squared or angular lug 2^a for receiving a 15 corresponding opening of the handle H, and it will, therefore, be apparent that when the actuator 1 is rocked by the manipulation of the handle H the lifting pawls 5-5 will be alternately moved in opposite directions thereby lifting the casing A and the upper rack C.

For the purpose of retaining the casing and rack C in the positions to which they are elevated by the manipulation of the lifting pawls 5-5, the sustaining pawls 8-8 are provided, the same being pivoted as shown at 9 to the side wall of the casing A.

These sustaining pawls 8-8 are adapted to be normally pressed in toward the shouldered edges of the racks, but when it is desired to collapse the jack, that is, permit the casing A and upper rack bar C to descend, it is necessary that the sustaining pawls be temporarily held out of the path of the shouldered racks, and to that end, each sustaining pawl is provided with a manually set controlling device which either places the pawl under compression or tension, according to whether the jack is to perform lifting or lowering service. As will be seen from the drawings this means preferably consists of a spindle member 10 which carries therewith a spring S comprising a radially projecting portion 11 looped as indicated at 12 and continued to form a coiled portion 13 adapted to engage with the intermediate part of an adjacent pawl 5 to counteract the force of its spring 7 while the loop 12 also receives one end of a looped tensioning and compression spring 14 whose free end 15 is eccentrically connected to the sustaining pawl 8.

When it is desired to manipulate the jack to elevate an object, the thumb-grips 16 carried by the projecting pins of the spindle 10 are set in the full line position shown in Figures 1 and 2, and in this position the looped parts 14 are placed under compression thereby to force the free ends 8^a of the sustaining pawls into the teeth or shoulders of the rack bars so that upon each reciprocation of the actuator 1 the lower lifting pawl will cause the member A to move upwardly and thereby elevate the lower sustaining pawl 8 to the next tooth above, and in turn

the upper lifting pawl will elevate the rack bar C so that the upper sustaining pawl 8 will engage the next tooth or shoulder below on the rack C.

To prevent the lifting pawls 5-5 from 70 overreaching in their movement the top and bottom walls of the casing A are provided with guiding portions 6^a.

When it is desired to permit the jack to collapse and lower the object, the thumb-grips 16 are shifted to the substantially vertical positions shown by dotted lines in Figure 1, thereby having the effect of placing the sustaining pawls 8-8 under the tension of the looped springs 14, and thrusting the 80 coiled part 13 into engagement with the lifting pawls 5 to temporarily push the lifting pawls out of engagement with the shoulders while the sustaining pawls are holding or supporting the load. In other words the 85 spring 13 will push the pawls 5 backwardly after the load is shifted from 5 to 8, and in the lowering process the ends 8^a of the pawls are not in contact with the shoulders of the rack until the same are forced into that position by the descent of the pawls 5. In that connection it may be pointed out that the 90 operation of the lifting pawls 5 and sustaining pawls 8 are substantially the same as disclosed in my copending application Serial 95 No. 710,277, filed May 1, 1924.

As will be observed from Figure 7, the thumb-grip levers 16 are provided with spring pressed catch members 17 which co-operate with the raised abutment segments 18 thereby to hold the said levers in the desired set positions 90° apart.

As previously indicated, this jack can be used as a single or double acting jack. That is, either the rack B or the rack C can be 105 operated independently of the other by the proper manipulation of the thumb-grips 16. For example, if it is desired to lift an object from the ground by the use of the lifting lug F, and it is not desired to elevate the 110 rack C to avoid interference with a superposed object, it is only necessary to place the thumb-grip 16 for the rack C in the dotted line position shown in Figure 1, leaving the other thumb-grip for the rack B in 115 the full line position shown. In that way the manipulation of the actuator 1 will not cause the lifting of the rack C and will permit the same to remain stationary.

Therefore, it will be understood that either 120 or both of the rack bars B and C may be operated, according to the position in which the springs S are set by the manipulation of the thumb-grip levers 16. By selectively controlling or setting the springs S in the 125 desired position, it will be readily apparent that either a single or double acting jack is readily provided.

From the foregoing, it will be apparent that the present invention includes a simple 130

and practical organization of parts which provide a lifting jack comprising a pair of rack bars relatively movable to each other and having reversely shouldered bases, the 5 said rack bars being interlocked with the casing or housing and having novel lifting and sustaining means for holding an object elevated or permitting it to descend as desired.

10 I claim:—

1. A lifting jack including a casing, rack bars fitted within opposite ends of said casing and adjustable in opposite directions, a rockable actuator journaled in the opposite 15 side walls of the casing, sustaining pawls carried by the inside of the casing, and adapted to engage the rack bars, and lifting pawls pivotally carried by the rockable actuator and disposed in opposite directions 20 between the rack bars and engaging therewith.

2. A lifting jack including a casing, rack bars fitted within opposite ends of the casing and projecting therefrom, a bearing foot carried by the rack bar projecting from the bottom of the casing and a lifting horn carried by the rack bar projecting from the top of the casing, sustaining pawls pivoted to the inside of the casing, an actuator having an exterior operating connection journaled in the opposite side walls of the casing, and lifting pawls pivotally carried by said actuator and housed within the casing and engaging the pawls of the rack bars also concealed within the casing.

3. A lifting jack including a casing, rack bars fitted within opposite ends of the casing and adjustable in opposite directions, a rockable actuator journaled in the opposite side 40 walls of the casing and consisting of a bearing portion and opposite bifurcated portions, spring-pressed rack engaging lifting pawls pivoted in said bifurcated portion, and sustaining pawls carried by the inside 45 of the casing.

4. A lifting jack including a casing, rack bars fitted within opposite ends of said casing and adjustable in opposite directions, an actuator including a rockable pivot member 50 journaled in the casing between said rack bars, rack engaging lifting pawls carried by

said pivot member, rack engaging sustaining pawls carried by the casing, and spring means arranged within the casing for controlling the operation of said sustaining 55 pawls and the corresponding lifting pawls, and means for controlling said spring means comprising a shifter member mounted in the side wall of the casing and having an exteriorly arranged finger engaging portion. 60

5. A lifting jack including a casing, rack bars slidably fitted in opposite ends of the casing, an actuator pivoted within the casing between the rack bars and having an operating-lever engaging portion projecting 65 exteriorly of the casing, lifting pawls pivotally carried by the rockable actuator and disposed in opposite direction between the rack bars to engage therewith and sustaining pawls carried by the inside wall of the 70 casing for engaging with the racks, and controlling devices for said sustaining pawls, said devices comprising double looped springs eccentrically connected with said pawls and a pivot member journaled in the 75 side wall of the casing for carrying and manipulating said springs, and thumb levers carried by said pivot members and mounted on the outside of the casing.

6. A lifting jack including a casing, rack bars slidably fitted within opposite ends of the casing, a rockable actuator pivoted in opposite side walls of the casing between the rack bars, lifting pawls carried by the actuator, sustaining pawls carried by the casing, and means for simultaneously controlling a sustaining pawl and corresponding lifting pawl, said means comprising a pivot member journaled in the side wall of the casing and having an exterior finger engaging portion and a spring carried by the inner end of said pivot member and directly connected with the sustaining pawl at one end and having another end slidably engaging with the lifting pawl corresponding to said sustaining pawl.

In testimony whereof I hereunto affix my signature in the presence of two witnesses.
